ELECTRIC ORGAN

Harry F. Waters, New York, N. Y., assignor of
 fifteen per cent to P. R. Mallory & Co., Inc.,
 Indianapolis, Ind., a corporation of Delaware

Application December 30, 1936, Serial No. 118,321

4 Claims.

(Cl. 84—1)

This invention relates to electrical musical instruments.

An object of the invention is to improve electrical musical instruments, such as electric organs and the like.

Other objects of the invention will be apparent from the following description and accompanying drawings taken in connection with the appended claims.

10 The invention comprises the features of construction, combination of elements, arrangement of parts, and methods of manufacture and operation referred to above or which will be brought out and exemplified in the disclosure hereinafter set forth, including the illustrations in the drawings.

In the drawings:

Figure 1 is a circuit diagram of a portion of a circuit of an electric organ;

20 Figure 2 represents a modification thereof;

Figure 3 illustrates a further modification;

Figure 4 shows another modification of the invention embodying a tone disc;

Figure 5 is a face view of the disc used in Figure 4; and

Figure 6 is a face view of the disc used in Figure 3.

In electrical musical instruments, such as electric organs, it is desirable to simulate and, if possible, improve upon the results obtainable with the traditional mechanical instruments such as the conventional wind-operated pipe organs. Some pipe organ effects have heretofore been difficult, if not impossible, to attain in electric organs. For example, with a pipe organ as each new note is added to the organ output the volume is increased in proportion and as each individual note is cut off the volume is decreased proportionally. For such a result to be achieved with an electric organ of the types heretofore used, would require a very large number of individual oscillator circuits, a number practically impossible for standard commercial instruments.

According to one aspect of my invention this result is accomplished by generating in a single oscillator or sound frequency producing means a sound frequency of true pitch rich in harmonics and then filtering out the harmonics in various proportions to obtain the different tone qualities desired such as reed, flute, string, or diapason quality. There may preferably be one oscillator for each pitch desired.

The variations in volume output for each quality are preferably obtained according to the invention by varying the resistance or transmission

efficiency in the secondary or output circuits individual to each tone. The circuits may preferably be so arranged that only a small part of the oscillator output volume is utilized for each tone quality. For example, if it is desired to bring in a flute first and later add reed quality the flute will only take a part of the oscillator volume, the rest being held in reserve. Then when the reed is brought in that quality adds to the total sound volume. Likewise as each tablet or switch on the organ is pulled a predetermined increase in volume is obtained.

The build up obtained in present types of electrical musical instruments is generally absent or is insufficient to obtain the natural reproduction of organ volume when several tones are combined to form an ensemble.

With the present invention it is possible not only to obtain volume build up as the various qualities are added to the output but it is also possible for the artist to vary at will the amplitude of each tone quality produced independently of the amplitude of the other qualities. This advantage is not obtainable with present types of musical instruments nor is it possible in pipe organ construction without special equipment, such as the "Vox Hunana" in a separate sound chamber.

Another feature of my invention involves the provision of unifying means whereby electric variations of a plurality of tone frequencies are unified and converted into audible musical notes.

A further feature of the invention comprises the selective or simultaneous reproduction of a plurality of sounds from a single record element and combining or unifying the sounds thus reproduced.

While a preferred embodiment of the invention is described herein, it is contemplated that considerable variation may be made in the method of procedure and the construction of parts without departing from the spirit of the invention. In the following description and in the claims, parts will be identified by specific names for convenience, but they are intended to be as generic in their application to similar parts as the art will permit.

Referring to the drawings Figure 1 shows a portion of an electric organ circuit embodying features of the present invention. It will be appreciated that the complete organ circuit is very complicated, involving many repetitions of the unit circuit illustrated. The number of similar connected circuits will depend upon the range of the organ and may comprise for example, twelve,

thirty-two, forty-nine or sixty-one circuits or over, each one representing a separate pitch. Thus there may be an oscillator for each individual pure pitch and keys individual to that pitch, and where the tablet contacts are here shown as each being only a single contact pair, in fact each tablet controls a large number of contacts.

For a given pitch, then, there is provided an oscillator 10 adapted to generate audio-frequency electrical oscillations of a true pitch value and rich in harmonics. One type of oscillator which would be suitable for this purpose is shown in my Patent No. 2,070,344 wherein the condenser 31 and tube 38 comprise the principal parts of the oscillator and receive energy from battery 27 which corresponds to battery 11 in the present disclosure. With all the harmonics retained, the oscillations would, upon conversion to audible sound, have a reed quality. The oscillator 10 receives its energy from a battery or other D. C. source 11 and supplies its oscillations to a loud speaker 14 through output transformer 12 and output amplifier circuit 13.

A plurality of filter circuits for obtaining the various tone qualities are adapted to be selectively connected between the oscillator and the output transformer by means of the organ keys and tablets under control of the artist.

Similar circuits for the remaining pitch values desired are connected to the battery and output transformer by conductors 15 and 16.

The organ controls for each pitch include a solo key 17, an accompaniment key 18, and a pedal 19. The controls also include tablets associated with each key and the pedal for each tone quality such as reed, string, flute and diapason. Each tablet controls a large number of contacts, such as one contact pair for each note. In the drawings the contact pairs for the note generated by oscillator 10 are represented, it being understood that other contacts (not shown) are associated therewith so as to be operated at the same time when the tablet is pulled.

Tone tablet contacts 20, 21, 22 and 23 are associated with the solo key 17 and provide reed, string, flute and diapason, respectively. Tone tablet contacts 24, 25, 26 and 27 are similarly associated with the accompaniment key 18 and tablet contacts 28, 29, 30 and 31 are in like manner associated with the pedal 19.

A coupler tablet having contacts 32 and a unifying tablet having contacts 33 are also provided.

For each tone quality a filter circuit is provided which filters out the undesired frequencies in the harmonics-rich note produced by oscillator 10 so as to leave only the oscillations necessary to give the desired quality. For reed quality little if any filtering will be necessary; for string, flute and diapason various proportions of the various frequencies need to be filtered out. Filter circuit 34 (if required) is connected between the tone tablet contacts representing reed quality and the output transformer 12. An adjustable resistance 38 is connected in series with it. Filters 35, 36 and 37 and associated resistances 39, 40 and 41, respectively are similarly connected to the string, flute and diapason contacts.

Output amplifier 13 is provided with a volume control comprising variable resistance 42 controlled by pedal 43 for varying the output volume.

In the operation of the organ the artist may pull such tone tablets as are desired for the different manuals or for solo, accompaniment and pedal keys. Then on pressing the desired key, the oscillator output oscillations will be connected

through the key, tablet contact, resistor and filter to the output transformer thus supplying a note of the desired pitch and tone quality to the loud speaker.

If the artist pulls the coupler tablet 32 the solo key will be coupled with the pedal so that solo and pedal will be coupled and played together. If he operates the unifying tablet 33 string and flute of the pedal circuits will be unified or coupled with the solo key.

In Figure 2 an arrangement is shown whereby considerably less power is required for the operation of the instrument. In place of an oscillator continuously operating during the entire selection for each note a normally de-energized electromagnetic reed vibrator 50 is provided and has associated therewith an electromagnetic or microphonic pick-up 51. Instead of an electromagnetically operated reed the reed can be vibrated by compressed air and the air valve controlled by the electromagnet. The pick-up device 51 is associated with the organ circuits in the same way as oscillator 10. In this instance, however, the keys, for instance, solo key 52, in addition to connecting the oscillations through the tablet contacts and filters by key contacts 53 also connect a source of electric energy such as battery 55 to the electromagnetic vibrator through key contacts 54, thereby starting the reed into vibration. As soon as the key is released the circuits are disconnected and the vibrator stops.

Figure 3 shows a means for picking up a tone from a sound record, either artificially produced or recorded from a musically produced pure tone. While a photoelectric system is illustrated the invention is also applicable to pick-up from mechanical sound records or other oscillations. In the illustration a disc 60 of glass or other transparent material is adapted to be rotated by an electric motor 61 in front of a plurality of light sources 62 and 63 energized by battery 64 through switch 65.

Disc 60 has a concentric series of photographic sound record tracks 66 thereon as illustrated in Figure 6. For example, each record track may represent a pure pitch or frequency.

A plurality of photoelectric cells 67 and 68 are positioned on the opposite side of disc 60 from light sources 62 and 63 respectively. Electromagnetically actuated shutters 69 and 70 are positioned between the disc and the cells normally cutting off the light passing through the disc to the cells but allowing the light to pass in response to energization of the electromagnets 71 and 72 respectively. The electromagnets are controlled by switches such as 73 and 74, respectively and solo and accompaniment keys 75 and 76 respectively. Thus it is possible, by actuation of the proper contacts to allow cell 67 to pick up the recorded sound waves or to actuate both cells 67 and 68 at once.

With switch 74 closed, for example, electromagnet 71 is connected so as to be actuated by either of keys 75 or 76. With switch 73 closed instead of 74 both electromagnet 71 and electromagnet 72 are connected so as to be operated simultaneously by either of keys 75 or 76.

Cells 67 and 68 pick up from the same sound pitch track and are so located as to be one-quarter cycle out of phase whereby the two pitch waves will be combined in the output to yield a wave of twice the former frequency.

In Figures 4 and 5 means are shown for selectively reproducing from a single sound record element, containing a plurality of sound record-

ings, the sounds corresponding to any one of said recordings or for simultaneously reproducing the sounds from a plurality of said recordings.

This means includes a sound record disc of 5 transparent material, such as glass, upon which are several concentric rows of photographic tone recordings. Such a disc may be called a "tone disc". Associated with the tone disc is a second transparent disc having photographic impressions 10 of slits arranged thereon.

This may be called a "pitch disc." The two discs are mounted in parallel co-axial relation with the pitch disc arranged to rotate at various speeds with respect to the tone disc and a light 15 source is arranged to project light through the discs.

The apparatus is arranged to subject the entire pitch disc and tone disc to light issuing from one or more light sources and by providing a separate 20 shutter mechanism, or multiple unit light-sensitive cell, for each individual row of sound representations on the tone disc.

In the drawings, wherein is shown for the purpose of illustration, merely, one embodiment of 25 the invention, 101 designates the tone disc of the improved apparatus, said tone disc being non-rotatably fixed in place in any suitable manner. Arranged adjacent to the tone disc 101 is a pitch disc 102 which is supported for rotation with respect to the tone disc 101 in any suitable manner, said pitch disc being subjected to rotatory movement preferably by a electric motor 103 through the instrumentality of a transmission belt 104 which operates over pulleys mounted 30 on shaft 105 of the pitch disc 102 and the armature shaft of the motor.

Arranged on the tone disc 101 are groups of 35 representations of sound vibrations 120, said groups of representations preferably being in the form of a number of radial rows of representations as shown in Fig. 5. The sound representations may be impressed on the tone disc photographically or otherwise and the different groups of sound representations may represent tones of 40 different musical instruments, or the tone disc may be provided with representations which produce hitherto unknown tones. For the purpose of this disclosure it may be assumed that the various radial rows of sound representations correspond 45 to stops of an organ as such assumption will simplify the description of the invention. It may be considered, therefore, that each radial row of sound representations includes twenty-six tones, and that each radial row of sound representations 50 produce tones of a musical instrument different from the musical instruments the tones of which are produced by the sound representations of the other rows of sound representations.

The pitch disc 102 is provided with photographic or other sound producing impressions of 55 a large number of slits 121 arranged in concentric order; that is to say there are twenty-six concentric rows of spaced slits arranged one within the other on the pitch disc, the number and arrangement of the slits being calculated in accordance 60 with the known fact that the ratio of successive half tones in the even tempered scale is about 106 to 100. It will be noted that each adjacent pair of slits in any of the concentric rows of slits on 65 the pitch disc 102 are spaced apart a distance substantially equal to the width of the various radial rows of sound representations on the tone disc 101.

Arranged in a horizontal plane and in alinement with each radial row of sound representa- 70

tions 120 on the tone disc 101 is a housing 106 which encloses a suitable electric lamp 107. This housing is also provided with suitable condensing lenses 108 through which light rays from the lamp 107 pass. Interposed between the lamp housing 106 and the corresponding row of sound representations with which it is alined is a shutter mechanism 109. This shutter mechanism may be of any suitable construction and arrangement and as the construction and arrangement of such shutter mechanisms is well known it will not be necessary to describe same in detail herein. All that need be known for a complete understanding of this invention is that the shutter mechanism referred to includes a plurality of shutters 10 each individual one of which is arranged so that it covers a space on the pitch disc equal to the length and width of one sound representation in the radial row of sound representations with which the shutter mechanism is associated. In 15 other words there are twenty-six individual shutters operable in a manner to cause the sound representations with which they are respectively related to be exposed or masked as desired. It is extremely important to note that each and every 20 radial row of sound representations on the tone disc has a shutter mechanism and a light source associated therewith, hence any sound representation on the entire tone disc may be exposed by operating the associated shutter so as to permit 25 light from the associated light source to pass therethrough.

In order to operate the individual shutters of the shutter mechanisms 109 associated with the various radial rows of sound representations 120 of the tone disc I provide a keyboard 110 provided 30 with electrical contact elements 111 and 112 which are moved into contact with each other on depression of the keys of the keyboard. The contact elements 112 are connected by electrical 35 conductors 113 to electro-magnets, or other suitable means (not shown) one of which is associated with each individual shutter of the shutter mechanisms 109. By depressing a key of the keyboard 110 the associated electro-magnet is energized 40 whereby the shutter associated with said electro-magnet is operated to expose the sound representation on the tone disc to which the shutter relates.

Located behind the tone disc 101 is a plurality 45 of photoelectric cells 114, there being an independent photoelectric cell associated with each radial row of sound representations 120 on said tone disc. Also each photoelectric cell has associated with it an amplifying means 114a which 50 amplifies the rather feeble electrical values produced by the photoelectric cell to the desired point. As stated each and every radial row of sound representations 120 on the tone disc 101 has a photoelectric cell 114 and an amplifying 55 means 114a associated therewith, and leading from the amplifying means of each photoelectric cell are electrical conductors 115 which lead to a common amplifier 116. The amplifier 116 is connected by electrical conductors 117 to a suitable 60 sound producing apparatus 118 such as a loud speaker.

In the operation of my improved apparatus the light sources 107 associated with all of the radial 65 rows of sound representations 120 on the tone disc are lighted and the pitch disc is rotated and when the apparatus is silent all of the individual shutters of the various shutter mechanisms 109 are in the positions where they prevent passage of light 70 through the corresponding sound representations 75

on the tone disc. With the apparatus in the conditions described a key of the keyboard is depressed with the result that the shutter corresponding to said key is operated to unmask the sound representation associated with said shutter thereby permitting the slits in the rotating pitch disc to intercept the light from the associated light source and sweep said light across the associated sound representation, the light from one slit of the pitch disc commencing its passage across the sound representation just as the preceding slit moves away from said sound representation. In this manner one of said slits is always carrying light across the associated sound representation while the associated shutter is in an open condition, hence, the sound produced will be continuous and unbroken. The light which passes through the sound representation falls into an associated photoelectric cell 114 which translates the particular light value into corresponding electrical values, and the amplifying means associated with the photoelectric cell amplifies the feeble electrical values to the desired extent. These electrical values are then conducted to the amplifier 116 where they are amplified and pass then to the loud speaker where said electrical values are translated into sound. This procedure is followed as each shutter is operated hence any tone whose representation appears on the tone disc 101 may be sounded at any time and as many of said tones as desired may be sounded simultaneously.

It is apparent, therefore, that my improved apparatus is capable of very complete operation inasmuch as any tone may be reproduced at any time or as many of said tones as desired may be reproduced simultaneously in the operation of the apparatus.

If the keyboard of my improved apparatus included a separate key for each tone represented on the tone disc an arrangement would be present similar to that in connection with the use of a straight organ. However, this may not be desirable at all times, hence, I intend under certain circumstances to unify the keyboard mechanism of my improved apparatus in the manner in which a modern pipe organ is unified. In other words the keyboard mechanism of the improved apparatus will be provided with an electrical wiring system which renders possible the sounding of more than one tone on depression of a single key, or the sounding of a certain tone on depression of different keys. Also such unifying electrical system renders possible the operation of various other combinations which are very well understood by persons familiar with the pipe organ art, hence, such operations need not be described in detail herein.

In Figure 4 I have illustrated diagrammatically and in the simplest possible form the arrangement of unifying the keyboard mechanism of my improved apparatus and in this view 110 designates the keyboard mechanism while 119 designates generally the well known system of unifying a keyboard mechanism.

While the present invention, as to its objects and advantages, has been described herein as carried out in specific embodiments thereof, it is not desired to be limited thereby but it is intended to

cover the invention broadly within the spirit and scope of the appended claims.

What is claimed is:

1. In an electric sound producing system, a sound record element carrying a record path of a sound wave of uniform pitch, means for scanning said record path and electrically producing sound therefrom and a second means for scanning said same record path at a different phase from said first scanning means but at the same scanning speed and means for electrically combining the resulting energy whereby a frequency is reproduced different from that produced by a single scanning means.

2. An electric organ comprising a generator of electric current having the frequency characteristics of a musical note rich in harmonics, a sound output system for converting sound-frequency electric energy into audible sound, and means for supplying sound-frequency electric energy from said generator to said sound output system comprising a plurality of electric circuits, a filter in each of said circuits, each of said filters transmitting the fundamental note produced by said generator, said individual filters having respectively different transmission characteristics for the harmonics produced by said generator whereby a different organ tone quality will be transmitted by each of said circuits, and organ controls for optionally connecting each of said circuits between said generator and said sound output system individually or a plurality in multiple.

3. An electric organ comprising a generator of electric current having the frequency characteristics of a musical note rich in harmonics, a sound output system for converting sound-frequency electric energy into audible sound, and means for supplying sound-frequency electric energy from said generator to said sound output system comprising a plurality of electric circuits, a filter in each of said circuits, each of said filters transmitting the fundamental note produced by said generator, said individual filters having respectively different transmission characteristics for the harmonics produced by said generator whereby a different organ tone quality will be transmitted by each of said circuits, current limiting means in each of said circuits for limiting the amount of electric sound frequency energy transmitted thereby to a small fraction of the total energy output of said generator, and organ controls for optionally connecting each of said circuits between said generator and said sound output system individually or a plurality in multiple, the energy volume of the fundamental note transmitted being greater when a plurality of tones are transmitted than when one tone is transmitted.

4. In an electric organ, a source of sound-frequency electric energy capable of being changed into a multiplicity of tone qualities, an output device for converting said energy into audible sound, and a plurality of channels for transmitting respectively different tone qualities to said output device from said source, and a means within a channel for limiting the amount of energy transmitted thereby to a portion of the total energy produced by said source.

HARRY F. WATERS.
